**DYE TRANSFER PROCESS FOR FORMING
MOTION PICTURE SOUND TRACK**

Juergen H. H. Keller and Robert H. Sprague, Chelmsford, Mass., assignors to Itek Corporation, Lexington, Mass.

No Drawing. Filed Apr. 4, 1969, Ser. No. 813,759

3 Claims

ABSTRACT OF THE DISCLOSURE

A light-absorptive image is placed on a record surface, such as a sound track on film, by forming a hardened gelatin or similar absorptive image, imbibing a dye into the image, transferring the dye to the record surface and fixing or mordanting the dye therein. The dye, normally highly unstable, is unexpectedly light stable in its mordanted form, and absorbs radiation in the range from about 650 to 1000 mm. Suitable dyes are certain cyanine dyes.

BACKGROUND OF THE INVENTION

In a number of arts, and the formation of sound strips is typical of one such art, it is desirable to form a predetermined pattern of light-absorptive material on a surface. This pattern must be highly light absorptive at least in a certain spectrum of radiation, and in the sound strip art, this spectrum generally should be from about 650 to about 1000 mm., usually with a maximum response around 840 mm. This is the normal peak output of projector lamps.

The conventional way at present of producing sound strips is to form a silver photographic image corresponding to the predetermined pattern to be recorded. This requires, therefore, that the complete photographic process of development, fixing, etc., be carried out for each sound strip that is produced. It is highly desirable, therefore, to develop a simpler way to produce sound strips in which a single physical image body can be produced, and the light absorptive pattern reproduced repetitively from this image body.

In the past, it has been impossible to devise such a repetitive process for sound strips and similar uses. Among other things, the dyes which might be useful in a dye-transfer process have been characterized by having the wrong spectral absorption or by being unstable. The requirements of a dye for use in a transfer process include a number of chemical and physical chemical properties such as solubility in water, and the ability to diffuse into a gelatin or similar layer, coupled with the ability to be diffused out of the layer and fixed onto an image-receiving surface. These properties have been found in a number of materials for conventional photographic purposes, and expert photographers still believe that the best color photographs are made by a dye transfer process. Unhappily, similar dyes having absorptive peaks in the infra-red ranges are not readily available or are highly unstable.

SUMMARY OF THE INVENTION

We have now found that certain dyes are normally highly unstable to the extent that in bulk or in solution they bleach out almost immediately in normal room light, but when employed according to our invention, do produce a sound strip having an unexpected degree of stability. This is all the more unexpected because their normal use as sensitizing dyes depends on their being easily made colorless or dissolved out of a photo-

2

graphic emulsion. A preferred species of dye, as described herein, has been prepared.

According to the present invention, a dye of the desired class is dissolved in aqueous solution, is imbibed into a preformed image of gelatin or similar material, corresponding to a record to be produced, is transferred from said image to the record surface, and is fixed or mordanted on the record surface to form a light stable record capable of absorbing radiation in the range from about 650 to about 1000 millimicrons with a substantial or peak response in the range of about 841 millimicrons. In a presently preferred form of the invention, the record being produced is a sound track.

According to this invention, a color material is imbibed into a master image material and transferred to a recording surface wherein it is fixed. It is understood that the imbibed color material may be one of two reactive materials operable to form an insoluble, light stable radiation absorber, the other material being contained on or in the recording surface.

The type of dye material which has been found satisfactory is one which is soluble in aqueous solution and capable of being diffused either into a gelatin layer or into a similar layer such as an acrylic coating or mixed acrylic-gelatin coating or other layer conventionally used in the photographic industry. It is capable of being fixed onto the record surface by means of a mordant or the like. Its spectral absorption is essentially in the 650 mm. to 1000 mm. range, and preferably peaks at about 840 mm. In aqueous solution, it is highly unstable and is substantially bleached out almost immediately in ordinary room light. In mordanted form such as a salt of a heavy metal such as thorium or the like or a polymeric salt-forming material, it is extremely light stable and is capable of being essentially permanently affixed to a surface, is essentially non-diffusing, and effectively absorbs radiation from usual projector lamps.

A suitable dye material has the general formula:

45 wherein:

n is 3 or 4;

*R*₁ and *R*₂ are benzyl or lower alkyl;

Y=suitable cation, such as alkali or alkaline earth metal cation, e.g., *Na*⁺, *K*⁺ and *Li*⁺.

50 *X*₁ and *X*₂ are the same or different elements necessary to complete a thiazole or substituted thiazole ring or a benzoxazole or naphthoxazole ring.

55 While *X*₁ and *X*₂ in the general formula may be the same or different, it has generally been found that the specular absorption of the dye material is in the preferred specular region if *X*₁ and *X*₂ represent the elements to complete a thiazole or substituted thiazole ring when *n* equals 3, and if *X*₁ and *X*₂ represent the elements necessary to complete a benzoxazole or naphthoxazole ring when *n* equals 4.

DETAILED DESCRIPTION OF THE INVENTION

65 A number of dye images have been formed and transferred to a suitable record base such as a support base for a sound track. For the purpose of comparative analysis, the following examples will be presented employing the same dye material in each example and employing reproducible procedures for the production of images on which measurements can conveniently be made. Thus, a step tablet was employed in these examples instead of a

sound track as a preferred means of obtaining meaningful measurements.

EXAMPLE I

A dye material was prepared as follows:

2-methylbenzothiazole 7.4 grams were combined with 6 grams of 1,3-propane sulfone and heated for 2½ hours on an oil-bath at 145°. The resulting sticky mass was dissolved in methanol. Acetone was added and on standing crystals formed, which were filtered off, washed with acetone and dried. 3.8 grams of quaternary salt were obtained.

2.4 grams of the above material was combined with 2.2 grams of glutaconaldehyde dianilide hydrochloride in 60 cc. absolute ethanol. 2 grams of piperidine were added and the mixture was stirred for 10 minutes at room temperature. A heavy precipitate formed during this time. The precipitate was filtered off and washed with methanol and acetone. After drying a crude material was obtained, and dissolved in boiling methanol. The solution was filtered hot, concentrated to about ½ its volume and cooled. After filtration, washing and drying golden-green crystals were obtained.

The dye, anhydro - 3,3'-bis (3-sulfopropyl) thiatricarbocyanine hydroxide, piperidine salt, has the following structural formula:

A hardened gelatin matrix was made by normal photographic procedures (for example silver halide or photoconductor emulsion gelatin relief images, e.g., U.S. Ser. Nos. 712,931, 713,022, 713,212 all filed on Mar. 14, 1968) from a sheet of commercially available matrix film. The film was exposed through a silver step tablet. After exposure and processing to form a hardened gelatin matrix, the matrix was dyed by immersing in a 0.2% aqueous solution of dye brought to pH 3.6 by the addition of ½% by volume of 10% acetic acid. After dyeing, the matrix was twice rinsed with 1% acetic acid to remove surface dye.

Commercial dye transfer paper was conditioned at 50° C. The dyed matrix was also conditioned to 50° C. (without drying), and the dyed surface of the matrix was placed in contact with the active surface of the dye transfer paper for two minutes at 50° C. The two layers were then separated, and the image of the dye material was found to be transferred to the dye transfer paper, and mordanted therein by the transfer paper's mordant. D_{max} of the transferred dye was 2.5, and D_{min} was 0.19.

The dye image on the transfer paper was then exposed to radiation including infra-red radiation by placing it in the film-mounting portion of a commercial 35 mm. photographic projector using a 300 watt projection lamp. The projector was not blower cooled, and the temperature inside the projector was not externally controlled. At the end of a 2 hour exposure in the projector, there was no visible decrease in color and the measured D_{max} of the image remained at 2.5.

EXAMPLE II

A hardened gelatin matrix was prepared and dyed according to the procedure of Example I. It was then transferred to a film substrate coated with a gelatin layer containing poly-4-vinyl pyridine metho-p-toluene sulfonate as a polymeric mordant. The resulting D_{max} was 0.78, D_{min} 0.05. The transferred mordanted dye image was stable upon exposure to intense infrared light as in a photographic projector.

EXAMPLE III

A hardened gelatin matrix was prepared on a matrix film using light sensitive titanium dioxide. The film and its photographic treatment are disclosed in U.S. Pat. No. 3,380,823.

The hardened gelatin matrix was dyed according to the procedure of Example I, and the dye image transferred to commercial dye transfer paper. D_{max} of the transferred dye image was 1.2, and the dye showed no fading either after exposure in a projector as in Example I, or after several days' exposure to direct sunlight.

EXAMPLE IV

The matrix employed in Example III was dyed and rinsed. It was thereafter transferred to the film employed in Example II including as a polymeric mordant poly-4-vinyl pyridine metho-p-toluene sulfonate. D_{max} of the transferred dye was 0.97, D_{min} was 0.03. The transferred mordanted dye image was light stable.

EXAMPLE V

The mordanted gelatin layer of Example II was directly dyed by immersion in a 0.2 solution of the dye at a pH of 3.6, and a temperature of 50° C. for 3 minutes. After rinsing and drying, the film was uniformly dyed, and had a D_{max} of 1.5. The color and density of the layer was not visibly changed on exposure of the layer in a projector such as disclosed in Example I.

EXAMPLE VI

The procedures of Examples I through V may be employed for the formation of sound tracks conventionally used in moving picture film. The resulting sound tracks have a high absorption density, particularly in the range of about 650 to about 1000 mm., and more specifically in the range of about 840 mm. which corresponds typically to approximately the maximum emission range of ordinary sound projector lamps. The sound track is highly efficient in the absorption of light from such lamps, and is virtually completely stable for exposures to such radiation corresponding to the use of sound tracks for many hundreds of performances.

In addition to the dye employed in Examples I through V, there may also be employed other members of the class corresponding to the general formula:

In the formula, X_1 and X_2 , n , Y and R_1 and R_2 have the values hereinbefore defined.

In addition to the dyes according to this formula, dyes where X_1 represents elements to complete a quinaldine ring appear suited to this invention. Specifically, the following two dyes are noted:

In general, it has been found that the light absorption characteristics of the dyes are closely in line with the maximum emission of projector lamps particularly where there is the proper interrelationship between the chain

length designated by n , and the ring structure as designated by X_1 and X_2 . For example, where n is 3, it is preferred to use a thiazole or a substituted thiazole ring compound to produce the spectral range most suited to sound strips. When n is 4 it is preferred to use ring elements corresponding to a benzoxazole or naphthoxazole ring. It has also been found that employing benzyl or lower alkyl radicals has only a very slight effect on the spectral absorption range.

It has previously been known that dye materials of this general formula can be prepared, and such dye materials are generally characterized by being highly absorptive of radiation in specific spectral ranges, of being rapidly decomposed by such radiation, and by being capable of transferring the energy absorbed from such radiation within a photographic film structure, to a silver halide complex in such manner that these materials are satisfactory photosensitizing dyes. It has now been demonstrated that the materials according to the present invention can be fixed in an insoluble form such as for example by mordanting and when so made insoluble, are light stable and are particularly well suited for the production of sound tracks and for other uses where the dye must be stable to the absorbed light.

The mordant according to this invention is a heavy metal, polymeric, or other salt-forming material incorporated in the record member and capable of forming an insoluble, essentially non-diffusing salt of the dye. A wide variety of mordants are known to be useful mordants in photographic chemistry, and one skilled in the art can select a convenient mordant for use in this invention. Suitable mordants are disclosed, for example, in Belgian Pat. No. 657,788, issued Apr. 30, 1965, in U.S. Pat. No. 2,839,401, in U.S. Pat. No. 2,945,006, in U.S. Pat. No. 2,768,078 and in numerous other patents.

What is claimed is:

1. A method of producing light-stable dye images from a repetitively useful master comprising forming a hardened gelatin master pattern corresponding to an image to be formed, imbibing into the hardened gelatin a dye having the formula:

5

wherein:

n is 3 or 4;
 R_1 and R_2 are benzyl or lower alkyl;
 Y =suitable cation;

X_1 and X_2 are the same or different elements necessary to complete a thiazole or substituted thiazole ring or a benzoxazole or naphthoxazole ring, and transferring the imbibed dye to a mordant-containing surface.

10 2. The process of claim 1 wherein the dye is anhydro-3,3'-bis(3-sulfopropyl)thiatricarbocyanine hydroxide, piperidinesalt.

15 3. A method of forming sound tracks from a dye having the formula:

20 wherein:

n is 3 or 4;
 R_1 and R_2 are benzyl or lower alkyl;
 Y =an alkali or alkaline earth metal cation;
 X_1 and X_2 are the same or different elements necessary to complete a thiazole or substituted thiazole ring or a benzoxazole or naphthoxazole ring, comprising forming a hardened gelatin master corresponding to the sound track, imbibing said dye into the gelatin master, transferring the dye to a film to receive a sound strip and mordanting the dye on the film.
